UNITED STATES PATENT OFFICE.

ALBERT B. ROTH, OF BROOKLYN, NEW YORK, ASSIGNOR, BY MESNE ASSIGNMENTS, TO
WILLIAM N. FLEISCHMANN, OF NEW YORK, N. Y.

COIN BOX FOR COIN-CONTROLLED MECHANISMS.

Application filed April 3, 1923. Serial No. 629,560.

To all whom it may concern:

Be it known that I, ALBERT B. ROTH, a citizen of the United States, and resident of the borough of Brooklyn, county of Kings, 5 city and State of New York, have invented certain new and useful Improvements in Coin Boxes for Coin-Controlled Mechanisms, of which the following is the specification.

10 The device, the subject of this invention is a box, safe or cabinet intended to ultimately receive the coin which passes into and controls the operation of vending machines or for coin controlled mechanisms.

15 The principal object of the invention is to produce a coin box, so constructed that, while in position, coins may enter the box freely, but when removed from its place of 20 operation, the box will be closed against the egress of coins.

Another object of the invention is to provide means for closing the coin slot, so that coins cannot be inserted or removed from the box and another object of the invention 25 is to close and lock the means, through which the coin slot closing device is operated, so that foreign devices or substances cannot be inserted into the box for the purpose of opening the coin slot to allow the 30 coins to pass outward therethrough.

The following is what I consider a good means of carrying out this invention and the accompanying drawing should be referred to for a complete understanding of 35 the specification which follows.

In the drawings:—

Fig. 1, shows my coin box in operative position, parts of the mechanism with which the box operates are shown in section.

40 Fig. 2, is an enlarged, top, plan view, showing the box in operative position.

Fig. 3, is a side elevation, partly in section of the view shown in Fig. 1.

45 Fig. 4, is an enlarged, side elevation and partial section, showing the box locking mechanism.

Similar reference numerals indicate like parts in all the figures where they appear.

50 While my coin box may be utilized with coin controlled mechanisms of any nature, in the drawings, I show it operating with a scales, but, however, as the construction of the scales or their operation, does not in any way change the construction or operation of 55 my coin box, I will merely indicate the

scales, describing the parts thereof, shown, but briefly.

The platform of the scales is shown at 5 and the base support for the platform at 6. The column 7, connected to the platform, 60 serves as an enclosing means for the vertical rod 8, which connects with the scale beam and it is in this column that I arrange the coin box, which I will describe in detail.

Within the column 7, I arrange a plurality 65 of lugs as shown at 9 and 10, which serve to support the coin box and which I will indicate, in its entirety at 11. A third lug 12 serves as a stop and guide for the coin box and the coin conduit 13 conveys the 70 coins from their entrance into the machine to the coin box.

The coin box 11 is an oblong casing formed of any suitable material, such as steel or aluminium and approximating the 75 top, though upon the two shortest sides of the box, I arrange ways 14 and 15, adapted to engage upon the lugs 9 and 10, to support the box. Extending upward from the top of the box 16, is a hopper or entrance 80 chute 17, adapted to be arranged in line with the coin chute or conduit 13 and within the column 7, I arrange another lug or projection 18 upon which is a bracket 19, the bracket 19 and lug 18 supports a pin 20, 85 which is provided with a spring 21, urging the pin toward the box.

The pin 20 enters the box, through the perforation 23 in one side thereof and for the purpose that shall be described later. 90 The bottom 24 of my coin box is hinged to the box, if desired, or may be provided with a tongue and groove as shown at 26, at one side thereof, the bar 27 of the lock 25, passing over the lug 28 in one side of the box, 95 to secure the bottom in position. It is through this bottom that the coin in the box is intended to be discharged.

Arranged within the box 11 and at the upper end thereof, is a lock containing casting 29, having projections or lugs 30 and 31, formed integral therewith. Through the lug or projection 30, a movable bar or barrier 32 passes. This barrier is urged upward by a spring 33. The barrier is provided with an oblong perforation as shown at 34, through which the pin 20 is adapted to pass, when the perforation 34 is brought into register with the perforation 23 in the side of the box 11. Pivoted to the lug or 110

2
projection 31 is a hooked lever 35, adapted to engage a projection 36 on the bar 32, to retain the spring 33 retracted. A link 37 extends from the lever 35 to a second lever 38, which is pivoted at 39 to a lug or projection 40 within the casing 29 and upon the platform 41, I arrange a slide 42, an open box shaped member having a slot 43 therethrough. The slide 42 is connected to the link 38, as shown at 44 and a spring 45 urges the slide forward, so that when the spring 45 is expanded, the slot 43 will be out of register with the passage through the coin chute 46 within the casing or box 11 and I may arrange a second coin chute 47 which will convey the coins, past the mechanism just described and into the body of the box 11.

The locking mechanism within the casing 29, may be therefore protected by an interior cover 48, shown as secured to the walls of the inner casing 29.

When the box is empty and out of the machine with which it operates, the pin 20 is not in the position shown, as that pin is secured in the machine. The bar 32 then, should be retracted and the hook 35 caused to engage the projection 36, holding the spring 33 retracted. The slide 42 will then be moved so that the passage through the chute 46 will be closed. In this condition, the box is placed in the machine, with which it is to be operated. The pin 20, entering through the perforations 23 and 34, will move the slide 42 into the position shown in Fig. 4, withdrawing the hook 35 from the projection 36. The bar 32 will move slightly upward, because of the oblong shape of the perforation 34. Now, when the box 11 is removed from the machine with which it operates, the pin 20 will be withdrawn from the perforations 23 and 34, allowing the slide 42 to move forward to again close the

passage through the chute 46 and at this time, the bar 32 will close the passage 45 through the perforation 23. The device can only be re-set by removing the bottom 24 of the box and then proceeding as above described.

It will be noted that the coin passage is 50 closed against movement of the coin in either direction and that the passage cannot be opened from the exterior of the box.

The shape and the size of my coin box and the parts thereof and each associated 55 part may be changed at will and other modifications may be made within the scope of the appended claims, without departing from the principle or sacrificing the advantages 60 of the invention.

Having carefully and fully described my invention, what I claim and desire to obtain is:—

1. A coin box having a coin slot, a spring 65 operated slidable member passing over said slot, means adapted to enter said box, to operate said slidable member, to prevent the insertion of said means.

2. A coin box having a plurality of passages entering said box, means controlling 70 said passages, means operating said controlling means to retain said passages open and means for closing said passages upon the withdrawal of the operating means.

3. A coin box having a coin chute entering therein, a slidable member adjacent thereto and adapted to close said chute, means for operating said slidable member to open said chute and means controlled by 80 said slidable member, for preventing the introduction of said operating means for said slidable member.

Signed at the city, county, and State of New York, this 23d day of March, 1923.

ALBERT B. ROTH.
